(57) CLAIM

The ornamental design for a case for electronic communications device, as shown and described.

DESCRIPTION

FIG. 1 is a front perspective view of a case for electronic communications device showing my new design in an environment of use;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a front perspective view showing the case for electronic communications device in isolation for clarity of disclosure;

FIG. 10 is a rear perspective view showing the case for electronic communications device in isolation for clarity of disclosure;

FIG. 11 is an exploded front perspective view showing the case for electronic communications device separated from the environmental front cover for clarity of disclosure;

FIG. 12 is an exploded rear perspective showing the case for electronic communications device separated from the environmental front cover for clarity of disclosure; and,

FIG. 13 is an enlarged detail view of the encircled portion of FIG. 6 to more clearly disclose the appearance of the textured surface of the side button; the appearance of the textured surface of this side button is also characteristic of the appearance of the textured surfaces of the upper two buttons on the opposite side of the case.

The dot-dash broken line circle in FIGS. 6 and 13 delineate a portion of the case for electronic communications device that is part of the claimed design and that is shown on an enlarged scale in FIG. 13. The dashed broken lines throughout the drawing figures depict portions of the case for electronic communications device that form no part of the
